UNITED STATES PATENT OFFICE.

MILLARD L. DUNHAM, OF NEW YORK, N. Y., ASSIGNOR OF ONE-FOURTH TO LOUIS DE F. MUNGER, OF NEW YORK, N. Y.

PISTON-RING.

1,241,835.

Specification of Letters Patent.

Patented Oct. 2, 1917.

Application filed April 18, 1916. Serial No. 91,854.

To all whom it may concern:

Be it known that I, MILLARD L. DUNHAM, citizen of the United States, and resident of the borough of Manhattan, in the city, 5 county, and State of New York, have invented certain new and useful Improvements in Piston-Rings, of which the following is a specification.

This invention relates to piston rings, and 10 consists in a certain method of treatment, or step in the manufacture of piston rings, whereby these devices are rendered more efficient and serviceable in the performance of the functions for which they are designed.

Piston rings are usually made from cast 15 iron, and rely for their outward tension, whereby gas tight relationship with the cylinder wall is provided, upon the inherent elasticity of the material from which cast, 20 in the restorative effort toward resumption of their original contour; after the inward compression to which they must be subjected in order to introduce the rings, upon a piston, within the cylinder. Thus the 25 rings are usually cast of a diameter greater than the inside diameter of the cylinder with which they are to be used, and are split at one point, by the removal of a portion of the ring material, leaving two opposed 30 ends, to provide space for the aforesaid inward compression; the space being of such extent only that when abridged by the inward compression for service, the opposed ends will have spaced relationship just sufficient to serve the purposes of heat expansion 35 and contraction in use.

A true bearing outwardly cannot be assured with a piston ring which has been singly cast or machined larger than cylinder 40 size, and a section removed to allow compressing to operating size, to secure the necessary tension. Nor will it serve to re-turn the ring when contracted. Rings thus ordinarily produced will not always assume the 45 form of a true circle when fitted to a cylinder, and a positive bearing of the ring cannot be obtained against the cylinder wall.

Under this ordinary method of piston ring manufacture the true circular form becomes 50 distorted when the ring is contracted to fit within the cylinder; the distortion consisting in portions of the ring, near its ends, lagging inwardly, leaving clearances between the outer peripheral surface of said 55 portions—over certain arcs—and the op-

posed portions of the cylinder wall. These clearances permit sufficient leakage to affect the cylinder compression.

Various means have been sought to rectify this deficiency in piston rings, and my present invention is directed to a novel, simple, and efficacious method, whereby a circular ring, produced in the ordinary way, is caused to have a true circular contour after it has been contracted to fit within a cylinder.

This method, briefly stated, consists in first cutting a piece out of a circular ring, in the usual manner; then in heating portions of said ring, including said ends and sections anterior thereof, to a degree of temperature 60 capable of rendering said heated portions ductile; and then, while in a ductile state, shaping said portions, as over a mandrel, to give them, equally, a distorted contour; wherein the ends aforesaid are inclined inwardly and said end portions caused to describe a segment of a circle whose diameter is slightly less than the diameter of the untreated portion of the ring in its free state.

The shaping operation aforesaid, effects 65 a distortion of the ring from a true circle; which distortion, upon cooling of the ring, becomes permanent as to the free state thereof.

The ring, as distorted, and while in a free 70 state, is of slightly less diameter in a medial line drawn from between its ends to the heel of said ring, that diameter graduating out to merge into the normal diameter of the non-distorted portion of the ring in its free 75 state.

The degree of distortion aforesaid is governed by the extent of the space separating the ring ends in its free state, which regulates the circle restorative movement of the 80 free ring portions in the contraction of the ring to its operative, cylinder fitting condition; in which it is required to have a true cylindrical contour. In this contracted state, the expansive effort of the ring causes 85 it to exert outward, radial bearing, in which the face of said ring, throughout its entire circumference, is in contacting, leak proof relation with the cylinder wall.

The ring shaped operation referred to begins, respectively, at each side of the ring, at a point intermediate its heel and the joint, and in the performance of said operation the ring is gripped, by a suitable tool, adjacent to said intermediate point, as a ful-

crum; and while ductile, is pressed against a form or mandrel whose contour is of appropriate character.

I have found that rings of ordinary cast iron, shaped while ductile to the requisite, described distortion, are possessed of adequate resiliency to fulfil their functions in service. Also, it may be stated that vanadium iron gives good results; and, undoubtedly, other alloys may be satisfactorily employed.

Other features and advantages of my said invention will hereinafter appear.

In the drawing:

15 Figure 1 is a plan view of a circular ring from which a section has been removed to permit contraction.

Fig. 2 is a similar view, showing the ring upon a mandrel, and one end portion thereof rendered ductile by heat, pressed against the mandrel to distort its shape.

Fig. 3 is a similar view of the ring, as partially treated, and fitted within a cylinder, and

25 Fig. 4 shows the ring, as treated at both end portions, and fitted within a cylinder.

In carrying out my improved method of producing piston rings, I take an annulus, as 1, of cast or other metal having a degree 30 of elasticity suitable for the purpose, and of oversize; that is to say, the outside diameter of the annulus is greater than the inside diameter of the cylinder for which it is designed. I then remove a section of said 35 annulus to thus leave the opposed ends 2, 3, separated by a space whose extent allows the contraction of said annulus to the desired, tensional, cylinder fitting area. Then the annulus is heated, over the ends and 40 portions 4, 5, thereof, representing the portions, anterior, respectively, to the ends 2, 3; and finally said portions are shaped, while ductile, out of the circular form of the annulus, as over a mandrel 6; whereby the 45 ends 2, 3, and the anterior portions 4, 5, are

caused to become permanently inclined inwardly, to describe, in the free state of the ring, a segment of a smaller circle.

The effect of the distortion described, when the ring is contracted, so as to bridge 50 the space separating its ends and fit with radial tension within its cylinder, is to allow the ring to assume a true circular contour over its entire circumference.

Variations may be resorted to within the 55 spirit and scope of my claimed invention.

I claim:

1. The method of producing a piston ring consisting in treating a metal annulus by localized heat and pressure whereby it is permanently distorted in a free state, said distortion enabling said annulus to assume a true circular contour in a contracted state.

2. The method of imparting even circumferential radial bearing to a piston ring in a 65 state as contracted from its free circular form, the same consisting in heating the ring end portions to render them ductile, and then in distorting said end portions out of the circular contour of said ring, the character of such distortion permitting said ring, when contracted, to possess true circular form.

3. The method of making piston rings which consists in producing an annular 75 blank, removing a section of said blank to provide opposed spaced ends, and in permanently distorting the end portions only of the blank, by inclining them inwardly, the character of said distortion enabling said 80 blank, when contracted for service tension, to possess true circular contour.

Signed at the borough of Manhattan, in the city, county and State of New York, this 14th day of April, A. D. 1916.

MILLARD L. DUNHAM.
